(57) **CLAIM**

We claim the ornamental design for a hybrid skateboard, scooter and bicycle frame, as shown and described.

DESCRIPTION

FIG. 1 is a front perspective view of the frame of the present invention showing my new design;

FIG. 2 is a bottom view thereof;

FIG. 3 is a rear view thereof;

FIG. 4 is a right side view thereof, the left side being a mirror image;

FIG. 5 is a frontal view thereof; and,

FIG. 6 is a top view thereof.

The broken lines showing the wheels, foot board, handle brake and handle bars are for illustrative purposes only and do not form part of the claimed design.
